UNITED STATES PATENT OFFICE

2,682,053

PLIER TYPE FASTENER DRIVING DEVICE

Henry Ruskin, Bayside, and Basil Zacharkiw,
Jamaica, N. Y., assignors to Speed Products
Company, Inc., Long Island City, N. Y., a cor-
poration of New York

Application August 23, 1951, Serial No. 243,242

13 Claims. (Cl. 1-49)

1

This invention is directed to an improved plier wherein a swingable cover is normally held removably interlocked with a companion staple receiving open top magazine and wherein full access may be had to the staple receiving channel of the open top magazine upon swinging the cover rearwardly away from the staple guideway communicating with and at the front part of the channel and wherein the cover and magazine as well as the anvil carrying base utilize common fulcrum means traversing the rear ends thereof to permit tiltable or hinged displacement of the magazine relative to the base and swingable movement of the cover to either fully open or close the magazine. One object of the invention is realized in interposing the hingedly associated cover, magazine and base, between a staple ejecting plunger arm in the form of a hollow cap and a spring controlled rockable handle normally unlocked from the plunger arm to permit the latter to swing rearwardly and bodily carry therewith the cover to fully open the magazine to render the staple channel completely accessible. Another important object resides in the provision of spaced wings on the manipulatable handle, normally unlocked from spaced posts carried by the plunger arm but instantly effective to interlock therewith upon rocking of the handle towards the base for initially shifting the latter against the vertical staple ejecting guideway of the magazine and subsequently but on the same actuating stroke of the handle shifting the plunger arm downwardly relative to the magazine and base for expelling the foremost staple of the staple strip in the magazine out of the latter and against the anvil for securing suitable sheets of material previously positioned on the anvil. Other important functional and structural features of the invention will appear from the following detailed specification taken with the accompanying drawings wherein:

Fig. 1 is a side view of the plier according to my invention illustrating the manipulatable or rockable handle unlocked from the staple plunger arm to permit the latter to be grasped, swung rearwardly, and carry with it the cover for the magazine to provide full access to the staple channel of the latter.

Fig. 2 is a side view of Fig. 1, shown partly broken away and in section, and further illustrating the plunger arm together with the cover swung rearwardly to fully open the magazine.

Fig. 2A is a plan view of the opened plier taken on the line 2A-2A of Fig. 2.

Fig. 2B is an enlarged side view taken on the line 2B-2B of Fig. 2A.

2

Fig. 3 is a view similar to Fig. 1 but showing the manipulatable handle rocked to interlock with the plunger arm prior to depressing the latter.

5 Fig. 4 is a view similar to Fig. 3 however showing the pivoted base lifted against the magazine after the handle has been further actuated.

10 Fig. 5 is a view along the lines of Fig. 4 but exhibiting the plunger arm depressed relative to the cover, magazine and base at the completion of the actuating stroke by the operator on the tiltable or rockable handle.

Fig. 6 is a transverse sectional view on the line 6-6 of Fig. 2.

15 Figs. 7, 8, 9 and 10 are transverse sectional views of Fig. 1 taken on the lines 7-7, 8-8, 9-9, and 10-10 respectively.

Fig. 11 is a perspective view of the plier.

20 Fig. 12 is a rear perspective view of Fig. 11, illustrating the plunger arm broken away.

Fig. 13 is a fragmentary plan view of Fig. 12, showing the cantilever leaf spring anchored to the rear end of the cover.

25 Fig. 14 is an elevational view taken on the line 14-14 of Fig. 5.

Fig. 15 is an enlarged sectional view on the line 15-15 of Fig. 5.

Fig. 16 is a perspective view of the ribbed cantilever leaf spring which normally holds the plunger arm elevated.

30 Fig. 17 is a sectional view on the line 17-17 of Fig. 16.

Fig. 18 is a sectional view on the line 18-18 of Fig. 3.

35 Fig. 19 is a fragmentary perspective view of the plier, specifically illustrating one of the shiftable fulcrum pins of the rockable handle at the lowest part of its relief slot of an associated side wall of the swingable base in the normal fully diverged relation of the handle and depressible plunger arm, and

40 Fig. 20 is a sectional view on the line 20-20 of Fig. 2.

In the drawings, the plier is generally designated P, and comprises, the open top staple receiving magazine M, the cover C, plunger arm PG, base B, and the loosely mounted rockable handle H.

45 Magazine or staple receiving arm M appropriately carries the fixed rail R (Fig. 2A) on which the staple strip S is slidably guided towards the staple guideway 10 (Fig. 2). A slidably guided follower F is mounted on the rail to shift the staple strip S towards the guideway 10.

50 Cover C embodies spaced sides 11 (Figs. 2A and 55 12) having at its rear ends spaced ears 12 piv-

totally retained on fulcrum pin F. Ears 13 of spaced sides 14 of magazine M are also pivotally mounted on fulcrum pin F and movably and closely straddle spaced ears 12 of cover C.

Upstanding sides 15 at the rear part of the base B straddle ears 13 of the magazine and are also pivotally mounted on fulcrum pin F.

Rear portions 16 of spaced sides 17 of the depressible plunger arm PG are likewise pivotally mounted on fulcrum pin F and swingably but closely straddle the upstanding sides 15 of base B.

Disposed transversely of cover C is a shiftable pin 20 having reduced portions 21 (Figs. 2A and 2B), loosely positioned in the spaced enlarged openings 22 in the spaced sides 11 of the cover.

Trained over and looped about pin 20 is the helicoidal spring LS having the end of its lower leg 23 appropriately retained by lug 24 of the slidably retained follower FW while the end upper leg 25 is suitably anchored to a projection 26 extending downwardly from the rear end of the cantilever spring L hereafter more particularly described.

By the arrangement disclosed the slidably retained follower FW moves rearwardly when the cover is swung rearwardly (Figs. 2 and 2A), thus fully exposing the inside guide channel SC defined by the walls of magazine M and rail R, permitting convenient insertion of an entire staple strip S through the open top of the magazine and into the staple guide channel. This channel SC of course communicates with the front staple guideway 10 as is well understood.

Plunger arm PG is a one piece sheet metal cap embodying top wall 30 from which depends the front wall 31 merged with depending sides 17 having their rear inwardly offset portions 16 pivoted on fulcrum pin F.

Anchored by spaced rivets 33 (Fig. 12) to the inside surface of top wall 30 is the branch 34 which is substantially normal to and integral with the staple driving blade 35 provided with the vertical slot 36, the spaced vertical sides of which are guided by the reduced portion 37 of the T-shaped lug 38 projecting from the bent spacer 39 (Fig. 2B) effectively interposed between and anchored to the spaced sides 11 of the swingable cover C, sides 11 being normally spaced from the top wall 30 of plunger arm PG (Figs. 1, 2 and 3) to allow pivotal displacement of the plunger arm relative to the cover and magazine when both of the latter are locked in a manner herein-after more particularly pointed out.

Leaf spring L has its front free end 40 sloping upwardly and forwardly to cooperate with the underface of top wall 30 of the plunger arm PG (Fig. 12) to normally hold the latter raised and the staple driving blade 35 above the staple guideway 10 receiving the foremost staple of a staple strip S.

The intermediate portion 41 (Fig. 2) of spring L abuts top wall 42 of cover C and part of this spring to the rear of the interconnecting top wall or stop 42 is arched over and seated against the inwardly overhanging flanges 43 extending from the spaced sides 11 of the cover which also embodies at the rear end thereof the inwardly turned flanges 44 including detents 45 projecting into and interlocking with notches 46 interrupting the rear end portion of spring L to hold the latter in place against longitudinal displacement. For stiffening purposes, spring L is provided with rib 48 along its central portion.

Interrupting the forward parts 50 of the spaced sides 14 of the magazine or staple containing M

are the aligned notches 51 having posterior upper parts provided with overhanging cams 52 which act on closing of the cover to shift projections 21 of the floating or loose pin 20 forwardly against the resistance of the looped spring LS. However on completion of the closing action, projections 21 are at the bottom of notches 51 but under cams 52 due to the recoil of spring LS, thereby holding the cover and magazine interlocked and of course closed at which time sides 14 of the magazine closely straddle sides 11 of the cover and the T-shaped lug 38 (Fig. 18) is seated against the lower stop wall 53 (Figs. 2 and 14) of dovetail shaped recess 54 interrupting the spaced inwardly turned flanges 55 constituting the front wall of the magazine. Inclined lips 56 (Figs. 2 and 18) cam blade 35 into staple guideway 10 when the plunger arm is depressed relative to the cover and magazine.

Spaced upstanding wings W of the rockable or pivoted handle H closely but movably straddle the upstanding spaced sides 15 of base B (Fig. 9) and depending sides 17 of the plunger arm or cap PG closely but movably straddle the spaced wings W but widely straddle the spaced sides 11 of cover C.

Spaced sides 15 of base B are provided with transversely aligned relief slots 60. Cylindrical posts 61 are anchored to and inwardly overhang the spaced wings W of the handle H. Posts 61 ride in relief slots 60 to constitute a loose connection.

A compressible helicoidal spring 62 (Fig. 1) is housed within hollow handle H and has its ends 63 and 64 retained by appropriate hooks 65 and 66 extending from the lower wall 67 of base B and lower wall 68 of the handle respectively. Spring 62 in the most widely diverged relation of the handle and base is expanded, thus holding anterior lip 70 against base B at which time it is important to observe that the spaced wings W (Fig. 1) are free and clear of the transversely aligned and spaced pins or posts 71 of the plunger arm PG. More specifically these posts are appropriately anchored to the inside faces of the spaced depending sides 17 of the plunger arm.

Spaced and upstanding wings W of the rotatable or rockable handle H are provided with aligned and reentrant notches 72 adapted to receive and interlock with the spaced and fixed pins or posts 71 of the plunger arm to pivotally depress the latter at a time when the cams or nose portions 73 are bearing down and driving posts 71. Normally, however, helicoidal spring 62 acts to maintain wings W of handle H unlocked from pins 71 of the plunger arm, and the handle is widely separated from the plunger arm (Fig. 1). Sides 11 of the plunger arm may be manually grasped and swung rearwardly (Fig. 2A). Consequently, cover C is also swung rearwardly since it is bodily carried by the plunger arm. It follows that full access may now be had to the staple receiving channel SC of the magazine to permit dropping into and load the latter with a staple strip S. Thereafter the plunger arm is swung towards the magazine and sides 11 of the cover become nested between sides 14 of the magazine and eventually projections 21 of the shiftable pin 20 strike the spaced cams 52 to be moved forwardly and on completion of the closing action, projections 21 due to the release of spring LS fall under to interlock with these cams. The cover is now locked against accidental opening. However towards the completion of the closing action of the cover, spaced

posts 71 of the plunger arm clear cams 73 and are disposed contiguous to the lower faces 74 of the aligned notches 72 at which time lip 70 of handle H due to the action of spring 62 bears against base B, thus the latter serves as a stop to limit divergence of the handle away from the base.

Briefly recapitulating, normally spring 62 pivotally retracts handle H until lip 70 strikes base B at which time as previously stated the spaced cams or noses 73 are free of, that is, unlocked from the driven and spaced posts 71 of the plunger arm (Fig. 1). Also the shiftable and spaced pins 61 carried by wings W of the handle are now at the lowest parts of the aligned relief slots 60 in the spaced side walls 15 of the base. Spring 62 also automatically retracts the pivoted base to provide maximum divergence between anvil A and the magazine. This relationship is also shown in Fig. 1 wherein the plunger arm is unlocked from the pivoted handle H although the reduced portions 21 of pin 20 of cover C are interlocked with spaced sides 50 of the magazine M. Now by grasping sides 17 of the plunger arm and lifting upwardly, both the plunger arm and cover C can be bodily swung rearwardly relative to the magazine M (Fig. 2A) for loading the latter with a strip of staples or to remove a clogged staple. Subsequently plunger arm PG and cover C are swung towards the magazine or staple containing arm M. Projections 21 strike cams 52 to tension loop spring LS and on complete closing of the cover these projections are held under these cams due to the recoil of spring LS.

Manual pressure on the handle in a direction towards base B causes the handle to pivot or rock and instantly pins 61 ride upwardly in the aligned relief slots 60 of the base to be against the upper ends of these slots which constitute fulcrum means for these pins. By such action wings W of the handle have shifted from their positions shown in Fig. 1 to their positions illustrated in Fig. 3, namely, with the aligned slots 72 thereof receiving the spaced posts 71 of the plunger. Further actuation of the handle in this same direction causes base B to be pivotally shifted towards the magazine to position the anvil A thereof against the magazine M (see Fig. 4). It should be realized that up to this time plunger arm PG has been idle, that is, it has not been pivoted downwardly relative to the magazine, cover and base but such action takes place only after the anvil has reached the magazine. This is accomplished on the completion of the operating stroke on the part of the operator and almost instantly as the spaced cams or lips 73 of wings W drive the spaced posts 71 downwardly, thereby causing the plunger arm to likewise pivot downwardly but only after the anvil contacts the base (Fig. 5). It is therefore apparent that the driving blade 35 meets the foremost staple of the strip and drives this staple against the anvil to clinch suitable material (not shown) previously mounted on the base. Hence the operating stroke of the pivoted handle has two important phases. In the first phase, the base is moved automatically to place the anvil against the magazine. In the second phase, the plunger arm is subsequently and automatically actuated relative to both base B and the pivoted intervening arm constituted by magazine M and its companion cover C. This operation, that is, these successive stages take place almost instantly when the operator manually squeezes the 75

pivoted handle towards the base and at the same time grasping the depressible plunger arm. Upon release of manual pressure on the handle and plunger arm, helicoidal spring 62 and leaf spring 5 L release their energy. Therefore spring 62 retracts the handle H and base B while the biased portion 40 of spring L causes the plunger arm to be automatically elevated. The plier is now fully open and again the spaced pins 61 are at the lowest parts of the relief slots 60 in the spaced sides 15 of the base.

Inwardly overhanging spaced detents 30 (Figs. 1, 2, 12 and 19) are struck out of the upstanding spaced sides 15 of base B and cooperate with the lower walls of aligned recesses 31 interrupting sides 14 of the magazine to prevent accidental upward pivotal displacement of the magazine out of the base but this may be accomplished by deliberately forcing the magazine M by these 20 detents.

Various changes may be made in details of construction and arrangement of parts without departing from the spirit of the invention or sacrificing any of the advantages inherent 25 therein.

We claim:

1. In a plier, a manipulatable handle embodying at its forward end a lip and having upstanding and spaced wings including upper portions 30 provided with aligned cam means and aligned notches disposed below said cam means, an anvil, a base carrying said anvil and interposed between said wings and seated on said lip, said base having upwardly extending spaced sides including 35 aligned relief slots, pins anchored to said wings and movably arranged in said slots, a staple receiving magazine interposed between said upwardly extending sides, a depressible plunger arm carrying a blade for expelling a staple out 40 of said magazine and having depending sides removably straddling said wings and upstanding sides, aligned and spaced posts carried by said depending sides and normally out of said notches and free of said cam means when said depending sides straddle said wings in the superimposed and 45 closed relation of said plunger arm over said magazine, a cover bodily carried by said plunger arm and removably receivable within said magazine, a staple driving blade carried by said plunger arm, means removably locking said cover and magazine; means common to said base, magazine, cover, and plunger arm and traversing the rear ends thereof for pivotally retaining said cover, magazine and plunger arm relative to said base, and spring means interposed between said handle 50 and base to hold the latter normally retracted and against said lip and concomitantly arrange said cam means out of the path of movement of said posts to permit bodily pivotal displacement of said plunger arm and cover away from said magazine.

2. The plier according to claim 1 wherein said spring means normally urges said handle away from said base and against said lip at which time said pins are disposed at the lower parts of said slots.

3. The plier according to claim 2 wherein upon manipulation of said handle in a direction towards said base, said pins are moved to the upper ends of said slots concomitantly interlocking the sides of said notches with said posts preparatory to shifting said base towards said magazine and said anvil against said magazine.

4. The plier according to claim 3 in that said posts after interlocking with the walls of said

notches, pivotally depress said plunger arm towards said cover, magazine and base and upon further manipulation of said handle towards said base but only after engagement of said anvil with said magazine shifting said blade downwardly in said magazine to expel the foremost staple in the latter.

5. The plier according to claim 1 further characterized in that said pins and slots constitute loose connections between said base and handle.

6. The plier according to claim 1 characterized further that stop means is provided on the upstanding sides of the base to cooperate with the sides of the magazine to prevent accidental removal of the magazine out of the base.

7. In a plier, a base, a plunger arm, a staple containing arm interposed between said plunger arm and base, means pivotally connecting the rear ends of said base, plunger arm and staple containing arm; a handle having loose connections with said base, posts carried by said plunger arm, cam means on said handle and spring means interposed between said handle and base to normally hold said cam means out of path of movement of said posts in the closed position of said plunger arm over said magazine and for holding said base diverged from said staple containing arm and against said handle.

8. The plier according to claim 7 wherein on each manipulating stroke of said handle towards said base the latter tilts towards and against said staple containing arm and thereafter said plunger arm tilts downwardly towards said staple containing arm and base for expelling the foremost staple in said staple containing arm.

9. The plier according to claim 7 wherein the handle closely straddles the base, widely straddles said staple containing arm, and the plunger arm widely straddles the staple containing arm and closely straddles the handle.

10. In a plier, a base, a plunger arm having a staple driving blade, a staple containing arm removably guiding said blade and interposed between said plunger arm and base, a cover bodily carried by and within said plunger arm for closing or opening said staple containing arm, means pivotally holding the rear ends of said base, staple containing arm, cover and plunger arm; a U-shaped handle having upstanding and spaced wings embodying loose connections with said base, spaced posts carried by said plunger arm, said upstanding and spaced wings having cam means

and notches below said cam means, and helicoidal spring means interposed between said handle and base to normally hold said base diverged from said staple containing arm and against said handle concomitantly positioning said notches substantially clear of said posts and said cam means out of path of movement of said posts prior to swinging said plunger arm from its closed position over said magazine to an open position rearwardly away from said magazine.

11. In a plier, a base having upstanding and transversely spaced sides including aligned relief slots, a plunger arm having a staple driving blade, a staple containing arm removably guiding said blade and interposed between said plunger arm and base and straddled by said sides, a cover bodily carried by and within said plunger arm for closing or opening said staple containing arm, means pivotally holding the rear ends of said base, staple containing arm, cover and plunger arm; a U-shaped handle having upstanding and spaced wings straddling said base and staple containing arm, spaced pins carried by said wings and movably guided by the walls of said slots, spaced posts carried by said plunger arm, said upstanding and spaced wings having cam means and notches below said cam means, and helicoidal spring means interposed between said handle and base to normally hold said base diverged from said staple containing arm and against said handle concomitantly positioning said notches substantially clear of said posts and said cam means out of path of movement of said posts on swinging said plunger arm from its closed position over said magazine to an open position rearwardly away from said magazine.

12. The plier according to claim 11 wherein the staple containing arm has a fully open channel for reception of a complete staple strip upon dropping thereof downwardly through the open top of said arm after swinging the plunger arm rearwardly and away from said wings.

13. The plier according to claim 12 characterized further in that the plunger arm widely telescopes over the staple containing arm and closely but removably straddles said wings.
